UNITED STATES PATENT OFFICE.

JOHN M. BEECH, OF CINCINNATI, OHIO, ASSIGNOR, BY MESNE ASSIGNMENTS,
OF ONE-HALF TO WILLIAM T. ADAMS, OF CORINTH, MISSISSIPPI.

HOT-AIR FURNACE.

SPECIFICATION forming part of Letters Patent No. 730,202, dated June 2, 1903.

Application filed February 19, 1903. Serial No. 144,035. (No model.)

To all whom it may concern:

Be it known that I, JOHN M. BEECH, a citizen of the United States of America, and a resident of Cincinnati, in the county of Hamilton and State of Ohio, have invented certain new and useful Improvements in Hot-Air Furnaces, of which the following is a specification.

This invention relates to certain improvements in furnaces, and has for its object to improve and simplify the construction and arrangement of the furnace-front, so that the same is made capable of complete removal in a simple and convenient manner, whereby a material saving both of time and labor is effected when it is desired to remove the furnace-front for the purpose of repairing the furnace or for other reasons, and it is rendered unnecessary to dismantle the furnace altogether in such cases.

The invention consists in certain novel features of the construction, combination, and arrangement of the several parts of the improved furnace whereby certain important advantages are attained and the device is made simpler, cheaper, and otherwise better adapted and more convenient for use, all as will be hereinafter fully set forth.

The novel features of the invention will be carefully defined in the claims.

In the accompanying drawings, which serve to illustrate my invention, Figure 1 is a front elevation showing a furnace embodying my improvements; and Fig. 2 is a perspective view showing the front portions of the improved furnace, the doors of the furnace-front being shown in opened position to disclose the interior arrangement. Fig. 3 is a view similar to Fig. 2, but illustrating the furnace with the grate-front removed to illustrate the means for supporting the same when in position for use. Fig. 4 is a sectional view taken vertically through the feed-section and illustrating in side elevation the means carried thereon for supporting the grate-front. Fig. 5 is a detached perspective view showing the combined grate-front and dead-plate of the furnace.

As shown in the views, 1 indicates the fire-box of the furnace, and 2 indicates the ash-

pit thereof, while 3 indicates as a whole the external shell or casing of the furnace. The furnace to which the invention is applied may be of any kind; but as herein shown the improvements are applied to a hot-air heating- 55 furnace.

4 indicates the grate, which divides the fire-box from the ash-pit and supports the fire, and 5 indicates the feed-section, herein shown as formed from a metal casting of an elongated rectangular form and arranged vertically in the front of the furnace, its upper part affording access to the fire-box for feeding the fire and its lower part affording access to the ash-pit for the removal of ashes. 60 There is no integral part of the feed-section for dividing its upper part from its lower part; but said section is continuously open from top to bottom, as shown in Fig. 3 of the drawings. 65

6 indicates a dead-plate which is extended transversely and horizontally across the upper part of the feed-section 5, and the fuel is adapted to be supplied to the fire-box above this dead-plate in feeding the fire. The dead-plate 6 is removably supported in the feed-section 5 upon side rests or projections 7 7, integrally formed upon the opposite side portions of said feed-section, and said dead-plate is also integrally formed with the grate-front 80

8, which, as shown in Figs. 2, 4, and 5, is extended vertically downward from the rear edge of the dead-plate and has its lower edge provided with integral pendent projections or lugs 9 9, the lower ends of which are adjacent to the forward edge of the grate 4, said lugs 9 being spaced apart to permit the insertion of a poker between them for stirring the fire and for the ready discharge of ashes. The lugs at the ends of the series 9 9 are made in 85 greater length, as shown at 10 10 in the drawings, and are bent slightly forward and adapted to rest upon the horizontal portions of L-shaped or angular stops or auxiliary rests 11 11, integrally formed upon the opposite side portions of the feed-section 5 below the rests 7, which extend under the ends of the dead-plate 6. The extended lugs 10 10 on the ends of the grate-front 8 are arranged to extend down in front of the vertical parts of 90

the L-shaped stops or rests 11, and said rests or stops serve to prevent the grate-front from "kicking up" or being pushed or forced upward when the fire is being stirred or stoked.

12 indicates a depending flange or lip extended along the front edge of the dead-plate 6 and adapted when said dead-plate is supported on the rests 7 to extend down in front of the forward ends of said rests in such a way as to prevent the dead-plate and grate-front from being pushed or slid rearwardly into the fire-box. The rear ends of the rests 7 are also formed with angular downwardly-bent extensions 13, adapted to take against the front of the grate-front 8 to prevent the same from warping and also to hold the combined grate-front and dead-plate solidly in place in the feed-section 5 and obviating draft at those points.

The feed-section is provided with a plurality of doors for closing its open front, and said doors are arranged one above another and are all hinged, as herein shown, at the one side of the feed-section, although this is immaterial to the invention. The dead-plate 6 is also arranged to stand in a slightly-inclined position when in place in the feed-section.

30 14 indicates the central door of the feed-section, and 15 indicates the upper door thereof, which latter when opened affords access to the fire-pot above the dead-plate for charging or stirring the fire. 16 indicates the lower door of the feed-section, and this when opened gives access to the ash-pit below the grate 4, so that ashes may be conveniently removed therefrom. The doors 14, 15, and 16 are arranged in such a way that their meeting edges are closely adjacent when the doors are closed, so that the open front of the feed-section may be tightly closed when desired, and the lower door, as herein shown, is provided with a damper 17 of any preferred kind.

45 The rests 7 at the sides of the feed-section 5 afford a secure and firm support for the ends of the dead-plate and the auxiliary rests or stops 11 prevent tilting or kicking up of the grate-front and dead-plate 50 when in place in the furnace, and at the same time it will be obvious that said combined dead-plate and grate-front may be conveniently and readily lifted out of the feed-section when desired, so as to afford free access 55 to the fire-box and ash-pit through the large opening of the feed-section, so that repairs may be very quickly and conveniently made.

The central door 14 of the feed-section may be left closed at ordinary times and will be 60 opened only when repairs are to be made and it is desirable to have free access to the interior of the furnace through the full opening of the feed-section. When it is desired to have access to the fire-box or to the ash-pit, 65 the upper or lower doors 15 and 16 may be opened independently of the central door.

The furnace constructed as above de-

scribed is of an extremely simple and inexpensive nature and is especially well adapted for use, since the structure of the front thereof affords very convenient access to the interior for making repairs, and since there is no obstruction whatever within the feed-section when the doors thereof have been opened and the combined dead-plate and 70 grate-front have been removed it will be seen that the repairs may be effected in a much quicker time than in furnaces as heretofore constructed. Since the front of the fire-box is also most liable to burn out and 80 require repairs, it is evident that the removable grate-front which forms the front portion or wall of the said fire-box considerably lessens the expense of repairs and permits of their being more easily made. It will also 85 be obvious from the above description that the furnace is capable of considerable modification without material departure from the principles and spirit of the invention, and for this reason I do not wish to limit myself 90 to the precise form and arrangement of the several parts of the device herein set forth.

Having thus described the invention, what I claim, and desire to secure by Letters Patent, is—

95 1. A furnace having a grate dividing its interior into an upper fire-box and a lower ash-pit and provided with a feed-section having an opening extended from its upper to its lower part, the upper part of the opening affording access to the fire-box and the lower part thereof affording access to the ash-pit in combination with a grate-front and a dead-plate extended transversely across the opening in the feed-section and removably supported therein, substantially as set forth.

100 2. A furnace having a grate dividing its interior into an upper fire-box and a lower ash-pit and provided with a feed-section having an opening extended from its upper to its lower part, the upper part of the opening affording access to the fire-box and the lower part thereof affording access to the ash-pit, said feed-section having side portions formed 105 with integral rests and a dead-plate extended transversely across the opening of the feed-section and having its ends removably supported upon the rests at the sides of the feed-section, substantially as set forth.

110 3. A furnace having a grate dividing its interior into an upper fire-box and a lower ash-pit and provided with a feed-section having an opening extended from its upper to its lower part, the upper part of said opening affording access to the fire-box and the lower 115 part thereof affording access to the ash-pit, said feed-section having side portions formed with integral rests and a dead-plate extended transversely of the opening in the feed-section and having its ends removably supported 120 upon the rests at the sides of the feed-section, said ends of the dead-plate having at their rear and forward parts portions depending at front and rear of the rests, to hold the dead-

plate in position thereon, substantially as set forth.

4. A furnace having a grate dividing its interior into a fire-box and an ash-pit and provided with a feed-section having an opening extended from its upper to its lower part, the upper part of said opening affording access to the fire-box and the lower part thereof affording access to the ash-pit and a part extended transversely across the opening of the feed-section and removably held therein and comprising a dead-plate horizontal in said opening and a grate-front integrally formed on and depending from the rear edge of the dead-plate, substantially as set forth.

5. A furnace having a grate dividing its interior into a fire-box and an ash-pit and provided with a feed-section having an opening extended from its upper to its lower part, the upper part of the opening affording access to the fire-box and the lower part thereof affording access to the ash-pit, the side portions

of the feed-section having rests the rear portions of which are extended downward and having, below said rests, L-shaped stops, and a combined grate-front and dead-plate extended transversely across the opening of the feed-section and removably supported on said rests and stops, the ends of the dead-plate being engaged upon the rests and the grate-front being extended down behind the downwardly-extended portions of the rests and having at opposite ends of its lower edge downwardly and forwardly directed lugs which are arranged in front of the vertical parts of the L-shaped stops and which rest upon the forwardly-extended parts of said stops, substantially as set forth.

Signed at Cincinnati, Ohio, this 16th day of February, 1903.

JOHN M. BEECH.
